United States Patent Office.

MELVIN JINCKS, OF DANSVILLE, NEW YORK.

Letters Patent No. 77,620, dated May 5, 1868.

IMPROVEMENT IN LAMP-BURNERS.

The Schedule referred to in these Letters Patent and making part of the same.

TO ALL WHOM IT MAY CONCERN:

Be it known that I, MELVIN JINCKS, of Dansville, in the county of Livingston, and State of New York, have invented certain new and useful Improvements in Lamp-Burners; and I do hereby declare that the following is a full, clear, and exact description thereof, reference being had to the accompanying drawings, and to the letters of reference marked thereon, which form a part of this specification, in which—

Figure 1 represents a plan view, with the cone removed.

Figure 2, sectional view of the same.

Figure 3, a plan showing the cone in place; and

Figure 4 a side elevation of my invention.

The nature of this invention consists in constructing a Lamp-burner so that it may be adapted to different-sized or style of chimneys, the same being effected by the means substantially as hereinafter set forth.

To enable others skilled in the art to make and employ my invention, I will now describe its construction and operation.

A represents the burner, provided with a platform, perforated, as shown in fig. 1. Said platform is also furnished with holes, d d, as seen in fig. 1, the object of which will be more fully apparent hereafter.

b b b designate three metal springs formed into two parts, as shown in fig. 4, and sliding back and forth in recesses or slots c c c, made in the platform of the burner. The lower ends of these springs are turned up through slots in said platform, and are secured therein by means of cap-pieces or nuts, so that the springs may be adjusted to suit the size of the chimney. These springs, it will be observed, are so constructed or shaped that when the chimney is inserted between them, they will instantly clasp it, and securely hold it in place.

B designates the cone, which is furnished at its outer edges, on the under side, with catches or notched projections, a a a, formed as seen in fig. 2. Said projections are made to fit in the recesses or holes, d d, in the platform of the burner, and, by means of said projections, the cone can be easily removed when it is desired to clean the burner.

e e e designate three spring-clips, which are secured, at one end, to the under side of the cone, and, passing up through apertures, f f, in said cone, are bent so as to hold the chimney securely in place. One of these clips is formed with a flange or projection, h, which, when pushed back, will enable the chimney to be inserted between said clips.

Thus it will be seen, by the foregoing, that I can accommodate my arrangement to chimneys of different sizes or styles, and also furnish a secure method of keeping the chimney in place.

Having thus fully described my invention, what I claim as new, and desire to secure by Letters Patent, is—

1. The sliding springs or holders b b, for the purpose of adjusting the same to different sizes of chimneys, substantially as described.

2. In combination with the above, I claim the burner A, cone B, spring-clips e e e, and flange or knob h, when all are constructed and arranged substantially in the manner and for the purpose set forth.

In testimony that I claim the foregoing as my own, I affix my signature in presence of two witnesses.

MELVIN JINCKS.
